[57] CLAIM

The ornamental design for a packaged air inflator set, substantially as shown and described.

DESCRIPTION

FIG. 1 is a front perspective view of a packaged air inflator set showing my new design;

FIG. 2 is the rear perspective view;

FIG. 3 is another rear perspective view showing the bottom and side not seen in FIG. 2;

FIG. 4 is a top plan view with the lid at a lowered position;

FIG. 5 is a front elevational view;

FIG. 6 is a rear elevational view;

FIG. 7 is a side elevational view; and

FIG. 8 is an elevational view thereof showing the side opposite that seen in FIG. 7.

FIG. 1

FIG. 2

FIG. 3
